UNITED STATES PATENT OFFICE.

BLANCHE EYSTER, OF ST. LOUIS, MISSOURI.

STEADYING AND HOLDING DEVICE FOR PICTURE FRAMES.

Application filed February 12, 1921. Serial No. 444,433.

To all whom it may concern:

Be it known that I, BLANCHE EYSTER, a citizen of the United States of America, and a resident of the city of St. Louis and 5 State of Missouri, have invented certain new and useful Improvements in a Steadying and Holding Device for Picture Frames, of which the following is a specification.

The primary object of this invention is to 10 provide an improved penetrating element in the form of a brad to be used in connection with picture frames, and the like, in the hanging thereof so that the frames can be swung outwardly from their hung positions.

15 Another object is to provide a device or attachment for a picture frame for holding the frame a distance from the wall on which it is hung.

A further object is to provide a picture 20 steadyng device with a pair of opposing projecting ends.

Other and further objects will appear in the specification and be specifically pointed out in the appended claims, reference being 25 had to the accompanying drawings exemplifying the invention, and in which,

Figure 1 is a perspective view of this improved device.

Figure 2 is a perspective view showing the 30 application of devices of this character in use in connection with a picture frame, and the wall from which it is hung.

Figure 3 is a vertical sectional view of Figure 2.

35 With reference to the drawings, this improved device is comprised of a body portion 1, of relatively thin sheet metal, and extended from each end 2 thereof in right angular disposition therefrom is a pointed 40 projection 3, and extended from the center of said body portion is a prong 4 having a pointed extended end 5, the prong 4 at its point of engagement with the body portion 1 as designated at 6 may be secured thereto 45 in a desirable manner, and it might be preferable that said prong be constructed of steel or other metal of sufficient hardness and insertably held in said body portion.

In the application of devices of this 50 proved character to picture frames, and the like, while a single device may be used, yet it is thought preferable to use a pair of devices to each frame. And as shown in Fig. 2 of the drawings each device is engaged to the rear of the frame 7, adjacent to the lower end thereof in which the pair of pro-

jections 3 of the device are imbeded in the frame so that when the frame is hung from the support 8 and adjusted in a straightened position, the frame is then borne against so that the pointed ends 5 of the respective prongs 4 will be imbedded or penetrated a short distance into the wall 9. The engaging positions of said prongs will prevent the frame from being swung from its straightly 60 hung position.

Devices of this improved character not only hold and retain picture frames against swinging from their properly arranged positions, but in addition serve to hold the picture frame away from the wall thereby providing a space or passage way 10 between the frame and the wall. This is for the purpose of preventing a pocket being formed 70 between the picture frame and the wall 75 which has heretofore been an occurrence in picture frame hanging, such pocket providing for an accumulation of dirt and dust which marks the wall, whereas with the space or passageway provided between the 80 frame and the wall, dirt accumulation between the frame and the wall is reduced to the minimum and in fact is practically prevented on account of such a spaced away arrangement providing for an air circulating passageway in which the dust particles 85 will be carried out of the passageway rather than be retained in it.

What I claim and desire to secure by 90 United States Letters Patent is:

1. A supporting device for a picture frame constructed of two parts, one of said parts being a sheet metal portion formed so as to provide a pair of spaced apart penetrating points extending in one direction, said metal portion having an aperture formed therein between the points thereof, said other part being a brad which is inserted through said aperture of said metal portion in opposite direction to said points of said metal portion, said metal portion when secured to the picture frame by the points thereof adapted to prevent said brad from becoming disengaged from the apertures of said metal portion. 100

2. A supporting device for a picture frame comprising a sheet metal portion formed so as to provide a pair of spaced apart penetrating points extending in one direction, and an insertable prong immediately extended from said portion in opposite direction to said points, said prong 110

being held in its extended position from said portion by the picture frame when said portion is secured against the picture frame by the points of said portion.

5. 3. A device for supporting a picture frame against swinging laterally along the wall from which it is hung, comprising a body

portion bearing a pointed projection for insertion into said frame, and an insertable brad to be extended from said body portion in a direction opposite from said projection having its head bear against said frame. 10

BLANCHE EYSTER.
